US0D1077552S

(12) United States Design Patent (10) Patent No.: US D1,077,552 S
(45) Date of Patent:  Jun. 3, 2025

(54) COFFEE MACHINE

(71) Applicant: BSH Hausgeräte GmbH, Munich (DE)

(72) Inventors: Sonja Bürzle, Illertissen (DE);
Cornelius Nissen, Munich (DE)

(73) Assignee: Hausgeräte GmbH, Munich (DE)

() Term: 15 Years

(21) Appl. No.: 35/520,295

(22) Filed: Feb. 26, 2024

(80) Hague Agreement Data

Int. Filing Date: Feb. 26, 2024

Int. Reg. No.: DM/235576

Int. Reg. Date: Feb. 26, 2024

Int. Reg. Pub. Date: Mar. 15, 2024
